UNITED STATES PATENT OFFICE.

ELICE ARSENOVITES, OF WASHINGTON, DISTRICT OF COLUMBIA.

CHAIN PUMP.

1,292,226.

Specification of Letters Patent.

Patented Jan. 21, 1919.

Application filed June 6, 1918. Serial No. 238,502.

To all whom it may concern:

Be it known that I, ELICE ARSENOVITES, a citizen of the United States, residing at Washington, District of Columbia, have invented certain new and useful Improvements in Chain Pumps, of which the following is a specification.

My invention relates to improvements in that class of pumps ordinarily known as chain pumps, and the object of the invention is to simplify and improve the construction of this class of pumps over the prior state of the art. To this end the invention consists in the novel construction and combination of parts, as will be hereinafter more in detail described and the asserted novelty specifically claimed.

I have fully and clearly illustrated my invention in the accompanying drawings, in which—

Figure 1 represents a side elevation of my invention as being ready for use.

Fig. 2 is a plan or top view of the same.

Fig. 3 represents a view of one of the buckets or disks which elevate the water carried by the elevator chain.

Figs. 4 and 5 represent detail views.

Similar letters of reference refer to similar parts throughout the several figures.

30 A designates the framework of the pump within which a troughlike receptacle B is held for the water raised from a well. Within this framework is provided a transverse shaft C, which carries a wheel or pulley D, the periphery of which is concave, over which is carried the pump chain E with the water elevating buckets L, the said chain passing centrally through the buckets which are passed loosely through the longer elevator pipe or tube so that room may be given the buckets to prevent contact with the inner surface of the longer pipe or tube. The framework which has been partly described heretofore has extension portions or legs F 45 the lower ends of which are rigidly secured to the platform which covers the well from which the water is drawn.

The transverse shaft has secured thereto near one end a pinion H which meshes with 50 a cog wheel G, the cog wheel G being secured to a short parallel shaft I each of which shafts have their bearings in the frame-

work of the pump on one side, and journaled in the framework A on the opposite end of the shaft is a pinion K within the cogs of 55 which meshes a pawl to prevent backlash of the shaft carrying the chain and buckets. This mechanism is operated by a hand wheel M, as shown in Figs. 1 and 2 of the drawings.

60 Detachably secured to the underside of the platform which covers the well is a suitable reservoir and which when the pump is not in use can be laid aside, it not being essentially connected with the pump, its office being to contain the water elevated by the pump. From the size of the longer pipe it will be seen that there will be plenty of room for the buckets to pass through the pipe without knocking against the inner surface 70 of the same and the motion of the water continuously flowing through the pipe when the pump is in operation, prevents freezing of the water in winter. When the operation of the pump ceases the water runs down the 75 annular space between the buckets and the tube.

The operation of the device is as follows: The operator when operating the pump turns the handwheel, the cog upon the short 80 shaft meshes with the pinion on the chain and bucket wheel shaft, the pinion upon the opposite end of the shaft is provided with a dog or pawl to prevent the shaft from backlash in operating the pump. The chain and buckets are passed up through the pipe and elevate the water from the well into the troughlike receptacle and it is then passed out from the receptacle.

Having thus described my invention, what 90 I claim as new and desire to secure by Letters Patent is:

1. The combination with a bucket wheel having a concave groove in its periphery in which are formed a series of narrow transverse slots, of chain carrying buckets adapted to engage in said slots, a discharge trough, long and short tubes extending from the bottom of said trough through which the said buckets travel and means for driving 100 the bucket wheel.

2. The combination with a bucket wheel having a concave groove in its periphery in which are formed a series of narrow trans-

verse slots, of chain carrying buckets adapted to engage in said slots, a discharge trough, long and short tubes extending from the bottom of said trough through which the 5 said buckets travel and means for driving said bucket wheel comprising a shaft and a pinion mounted thereon, a short shaft, a gear

wheel and a hand wheel mounted on said short shaft, said gear wheel and pinion being positioned within and said hand-wheel 10 without the limits of said discharge trough.

In testimony whereof I affix my signature.

ELICE ARSENOVITES.
